UNITED STATES PATENT OFFICE.

FRANK C. WATKINS, OF PHILADELPHIA, PENNSYLVANIA, ASSIGNOR, BY MESNE ASSIGNMENTS, TO THE UNITED STATES KROTOPHONE COMPANY, OF NEW YORK, N. Y.

TELEPHONE-TRANSMITTER.

SPECIFICATION forming part of Letters Patent No. 369,379, dated September 6, 1887.

Application filed December 24, 1886. Serial No. 222,476. (No model.)

To all whom it may concern:

Be it known that I, FRANK C. WATKINS, a citizen of the United States, residing at Philadelphia, in the county of Philadelphia and State of Pennsylvania, have invented certain new and useful Improvements in Telephone-Transmitters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to transmitters for telephones, and the object is to provide a device of this kind for transmitting an intermittent direct current on the main line, so as to dispense with an induction-coil, and therefore save the system from the annoyance due to induction; and to these ends the novelty consists in a vibrating diaphragm provided with a rearwardly-projecting face-plate, against the face of which rests a series of conducting-spheres supported and contained within a funnel-shaped cup, which is suitably suspended parallel to and in close proximity to said face-plate, as will be hereinafter more fully described, and particularly pointed out in the claim.

In the accompanying drawings the same letters of reference indicate the same parts of the invention.

Figure 1 is a diametrical section of my improved form of transmitter. Fig. 2 is a rear elevation of the same. Figs. 3 and 4 are modifications thereof.

A is an annular ring which forms the frame of the device, and secured to the front thereof by a flange, a, is an open-ended hood, B, having a bottom, b, provided with a central orifice, b', the hood, bottom, and flange being preferably made integral. Suspended parallel with and immediately in the rear of the bottom of the hood is a diaphragm, C, to the center of which is secured a face-plate, D, by a screw, e. Mounted in front of this face-plate so that its open end is approximately covered by the face is a conical metallic cup,

E, which contains a number of small carbon 50 or other electrically-conducting spheres, e, loosely contained therein, so as to form a connection between the face-plate and the interior of the metallic cup. The periphery of this cup has a series of integral ears, e', and 55 beginning from the adjusting-screw F a wire runs through one of these ears, thence around a screw or stud, i, through another ear, then around a second stud, k, then through the remaining ear and back to the starting-point on 60 the screw F, which is then adjusted so as to produce considerable tension on the wire n, which suspends the conical cup in a comparatively rigid yet elastic position in front of the face-plate, as above set forth.

G represents the line-wire, which is connected to the diaphragm from whence the current is conducted to the face-plate, carbon spheres, conical cup, its supporting-wires, and thence to the ground-wire H.

The peculiar manner of mounting the cup and of conducting the current from it to the diaphragm, through the medium of the movable spheres, enables me to produce the most satisfactory results, and the instrument, after 75 being once set up, requires no further adjusting whatever.

In the modifications shown in Figs. 3 and 4 the number of conical cups are increased to correspond to the distance or length of the 80 line, as on very long-distance lines it is desirable to increase the battery, and consequently amplify the transmitting principle.

Having thus fully described my improved transmitter, what I claim is—

In a transmitter, a series of conducting-receptacles and a diaphragm, in combination with a series of conducting-spheres loosely contained within said receptacles and forming a connection between said receptacles and 90 diaphragm, as set forth.

In testimony whereof I affix my signature in presence of two witnesses.

FRANK C. WATKINS.
